UNITED STATES PATENT OFFICE.

MELVILLE CLARK, OF CHICAGO, ILLINOIS, ASSIGNOR TO MELVILLE CLARK PIANO COMPANY, A CORPORATION OF ILLINOIS.

DRIVE MECHANISM FOR COMBINED PHONOGRAHS AND PLAYER-PIANOS.

1,246,053.

Specification of Letters Patent.

Patented Nov. 13, 1917.

Application filed February 21, 1916. Serial No. 79,526.

To all whom it may concern:

Be it known that I, MELVILLE CLARK, a citizen of the United States, residing at Chicago, in the county of Cook and State of 5 Illinois, have invented new and useful Improvements in Drive Mechanism for Combined Phonographs and Player-Pianos, of which the following is a specification, reference being had to the accompanying drawings, forming a part thereof.

The purpose of this invention is to combine in a single casing a phonograph mechanism and a player piano mechanism, and to arrange for driving the phonograph from 15 the same motor which drives the take-up roll of the player mechanism. The invention consists in the features and elements of construction contributing to this result and their combinations described and shown in 20 the drawings as indicated by the claims.

In the drawings:

Figure 1 is a perspective view of a player piano having a phonograph mechanism embodied in its casing in accordance with this 25 invention.

Fig. 2 is a plan sectional view of most of the drive gearing for the take-up roll and the phonograph.

Fig. 3 is a detail elevation of certain portions of the drive gearing shown in Fig. 2.

Fig. 4 is a detail elevation of a gear shifting device.

Fig. 5 is a detail view of a clutch shifting device for the take-up roll.

Fig. 6 is a diagrammatic view of the pneumatic connections between the tracker board and certain pneumatics adapted for automatic control of the two mechanisms.

Fig. 7 is a detail view of a disengageable 40 connection in a tempo-controlling means.

Fig. 8 is a detail elevation of speed-varying means for the rotary table of the phonograph.

Fig. 9 is a detail section showing a manually operable winding gear for the motor.

Fig. 10 is a detail section of a sound-controlling curtain for the phonograph amplifier.

Fig. 11 is a front detail elevation of a 50 spring motor for driving the mechanism associated with this invention.

Fig. 12 is a diagrammatic side elevation of certain gear trains of the motor shown in Fig. 11.

Fig. 13 is a detail of the motor brake.

Fig. 14 is a detail view of the speed-controlling cam for actuating the brake and the reversing train.

It may be understood that this combined phonograph and player piano is designed 60 primarily for rendering vocal or instrumental selections by means of the phonograph with piano accompaniment controlled by the usual form of perforated note sheet, shown at 1, in Fig. 1; the rotary record-carrying table of the phonograph is arranged to be driven at a uniform speed from the same motor shown at 2, as is regularly provided for driving the take-up roll, 3, of the player mechanism. In order, however, 70 that either the player piano or the phonograph may be operated independently when desired, it is necessary to make the driving connections such that either mechanism can be driven alone from the motor, 2.

This motor, 2, may be of any convenient type fitted with a speed-regulating governor and speed-varying means; it is shown in the drawings as a spring motor of substantial construction, and to render its relation to 80 the other parts sufficiently clear it must be described somewhat in detail. Referring to Figs. 11, 12, 13 and 14, it will be noted that the motor is mounted just beyond the casing carrying the take-up roll, 3. Its spring 85 drum, 2^a, is geared to a small pinion, 2^b, on the shaft, 2^c, carrying a gear, 2^d, meshing with a pinion, 2^e, on the shaft, 2^f. From this shaft motion is transmitted through spiral gearing to the so-called fly-ball or centrifugal 90 governor whose mode of operation is well understood and whose friction disk, 2^g, is engaged by a brake, 2^h, whose adjustments serve to control the speed of the motor. The shaft, 2^f, also carries a gear, 2ⁱ, meshing with 95 a gear, 2^k, which is carried on an arm, 2^l, mounted to swing about the axis of the shaft, 2^f, connecting the gear, 2^k, either with the gear, 2^m, on the take-up roll shaft or with the gear, 2ⁿ, for driving the pinion, 2°, 100 on the rewind shaft. The brake, 2^h, is carried by one arm of a bell crank lever, 2^q, whose other arm engages a cam slot, 2^r, in a slideable control bar, 2^s, whose movement in a direction parallel to the axis of the take-up roll, 3, effects the adjustment of the brake, 2^h, for varying the speed of the motor, 2; and even for holding it at rest. A second cam slot, 2^t, in the bar, 2^s, controls a bell crank, 2^u, connected by a link, 2^v, to the 110

swinging arm, 2¹, which carries the gear, 2^k, so that after the cam bar, 2^s, has been moved from its zero speed position to its maximum speed position by means of a hand lever, 2^w, 5 a further movement of the lever in the same direction shifts the gear, 2^k, through its neutral position and into mesh with the gear, 2ⁿ, for rewinding the note sheet with the motor running at maximum speed.

10 Now referring to Fig. 2, the record-carrying table of the phonograph will be found indicated by a dotted circle at, 4, and the spindle of this table is shown in section at 15 5, carrying a friction pulley or wheel, 6, whose periphery contacts with the face of the friction plate, 7, secured to the end of a shaft, 8, at whose opposite end a spur pinion, 9, mounted near the adjustable journal, 10, of the shaft, 8, stands in position to 20 mesh with the gear, 2^d, on the motor, 2. As above indicated, this gear is normally connected in the train which draws the take-up roll, 3, but since the phonograph table, 4, must be operated at a constant speed to 25 avoid varying the pitch of the music produced, and since it may be necessary from time to time to slightly vary the speed of the take-up roll, 3, for synchronizing the phonograph music with the player accom- 30 paniment, it is no longer feasible to drive the take-up roll directly from the motor 2, when both mechanisms are to be operated by said motor, and motion is, therefore, transmitted to the take-up roll, 3, through 35 a pinion, 11, on the shaft, 8, meshing with a gear, 12, whose face, 12^a, constitutes a friction plate in driving engagement with a friction wheel, 13, rotatively carried on a shaft, 14, but slidably longitudinally there- 40 of for varying its position on the face of the gear, 12, and thus varying the speed trans- 45 mitted. The shaft, 14, carries a bevel gear, 15, meshing with a similar bevel gear, 16, on a horizontal shaft, 17, provided with a dis- 50 engageable clutch, 18, connecting with the take-up roll, 3. A yoke, 19, engaging the grooved hub of the friction wheel, 13, and carried on a slidably mounted stem, 19^a, is 55 arranged to be shifted through a bell crank, 20, and links, 21, by means of a handle, 22, which is accessible just below the take-up 60 roll in the central open panel of the piano casing.

As to the operation, it may be understood 55 that the governor brake, 2^h, of the motor, 2, is first utilized for varying the speed of the phonograph table, 4, to insure that the phonograph record will be rendered in correct tune with the piano. Then by pressing the 60 knob, 23^a, on the rod, 23, the latch member, 24, is depressed to release the lower end of the bell crank, 25, permitting its upper and horizontal arm, 25^a, to swing downwardly and lower the stylus, 26, onto the phonograph record indicated at 27, in Fig. 3.

With the record standing at rest the stylus, 26, is placed approximately at the point at which the actual music begins, and the arm, 25^a, of the bell crank, 25, is then raised to lift the stylus, 26, just off the record, 27, 70 the bell crank, 25, being retained in its position by the latch member, 24, which automatically resumes the engagement illustrated in Fig. 3 under the tension of its spring, 28. A small motor pneumatic, 29, 75 connected to the lower end of the rod, 23, and thereby linked to the latch member, 24, is adapted to release the latch, 24, when collapsed, thus permitting the sound box, 30, and its stylus, 26, to be lowered by gravity 80 onto the record, 27. Fig. 6 illustrates dia- 85 grammatically the motor pneumatic, 29, connected with its primary pneumatic, 31, which is connected to a duct, 32, in the tracker board, 33, so that if the perforated note sheet which is to control the playing of the piano accompaniment to the phonograph music be provided with a perforation positioned to uncover the duct, 32, at the proper point in the accompaniment for the beginning 90 of the phonograph music, the note sheet will serve to automatically bring the phonograph into action by thus actuating the motor pneumatic, 29, which releases the latch member, 24, and permits the stylus, 95 26, to engage the record, 27. After ascertaining the correct speed for proper tuning 100 of the phonograph music and finding the proper initial position for the stylus, 26, the motor, 2, is first started at the ascertained 105 speed and begins to revolve the table, 4, and also the take-up roll, 3, driven through the medium of the friction wheel 13, en- 110 gaging the face of the gear, 12; the note sheet, 1, being advanced by the rotation of the take-up roll, 3, and having an aperture registering with the duct, 32, then automatically starts the phonograph music, and the operator can almost immediately note whether the accompaniment should go 115 slower or faster to be properly synchronized with the phonograph solo. Such synchronization is easily effected by shifting the friction wheel, 13, by means of the handle 22.

115 Although the perforated note sheet is especially cut to serve for controlling an accompaniment to a particular phonograph record, being preferably made by the automatic recording of the hand-played accompaniment of a competent artist, the lengthening or shortening of the paper note sheet, due to changes of humidity, may require that occasional adjustment of the speed-controlling handle be made during the ren- 120 dition of the piece to keep the accompaniment strictly synchronized. In addition to such changes of speed it may be desirable to arrange for temporarily varying the ratio of speed between the note sheet, 1, and 125 130

- the phonograph record, 27, and this may be effected automatically by means of a familiar step-by-step device, shown in detail in my Patent No. 1,013,862, dated Jan. 9, 1912, and indicated in Fig. 3 at 34. This device includes a rack, 35, connected by a link, 36, to the bell crank lever, 20; a gear, 37, meshing with the rack, 35, is arranged to be fed step-by-step in one direction by a motor pneumatic, 38, and similarly in the opposite direction by the pneumatic, 39, said pneumatics being controlled, respectively, by ducts, 40 and 41, as indicated in Fig. 6.
- 15 Since the note sheet controlling the accompaniment is especially made to fit the particular phonograph record, 27, there will be a particular point in the note sheet corresponding quite accurately to the last note of the phonograph music, and immediately following this point the note sheet may be perforated at a position to register with a duct, 42, controlling the primary pneumatic, 43, corresponding to a motor pneumatic, 44, which is connected by a link, 45, to the lower end of the bell crank, 25, so that collapse of motor pneumatic, 44, will draw the lever, 25, back into the notch of the latch member, 24, in which position it will be retained, and in moving to which position it will raise the stylus, 26, out of contact with the record disk, 27, and thus throw the phonograph out of action.
- Now if it is desired to operate the player piano mechanism without the phonograph, the phonograph mechanism is disconnected from the motor, 2, by slightly springing the shaft, 8, out of line far enough to disengage the teeth of the pinion, 9, from the teeth 40 of the gear, 2^d. This is done by shifting a cam lever, 46, mounted on the side wall, 2^x, of the motor casing to a position in which its notch, 46^a, engages the pin, 47, of the slidably mounted journal bearing, 10, for the shaft, 8, and the notch, 46^a, being at the high point of the cam, it will be evident that this movement serves to separate the pinion, 9, from the gear, 2^d. The notch, 46^a, is only a slight depression in the face 45 of the cam, but sufficient to retain the parts in this adjusted position.
- The shaft, 8, being thus thrown out of service, the take-up roll, 3, can no longer be driven through the clutch, 18. The slideable member of the clutch, 18, is connected through a shifter rod, 49, with the slideable member of a clutch, 50, on the shaft of the motor gear, 2^m, so that as the clutch, 18, is disengaged the clutch, 50, serves to couple 55 the shaft directly to the take-up roll, 3, and the movement of the shifter rod, 49, is effected by a slideable cam block, 51, connected directly to the cam lever, 46, as shown in Fig. 4. A follower roller, 52, on the end of 60 the shifter rod, 49, engages the cam face of the block, 51, as indicated in Fig. 5, and is maintained in such engagement by a spring, 53, conveniently disposed near the opposite end of the rod, 49, to react against the one wall, 53^a, of the tracker housing, 70 53^b. A link, 54, connected at one end to the cam lever, 46, and carrying at its opposite end a handle, 55, projecting through a slot in the wall, 53^b, of the tracker housing, provides the manually engageable adjusting means for the cam lever, 46, and sliding cam, 51. It will be clear from Figs. 4 and 5 that when the lever, 46, is moved to the middle position of its range, that is, with the pin, 47, engaged in the notch, 46^a, the follower roller, 52, will ride on the highest part, 51^a, of the cam, 51, thus effecting crowding engagement of the clutch, 50.
- When the player piano is operated without the phonograph, it may be desired to use 85 upon it such perforated note sheets as are provided for automatic control of the tempo by means of perforations positioned to register with the ducts, 40 and 41. Such perforations would effect actuation of the step-by-step device, 34, as fully described in my said Patent No. 1,013,862 and to render this operative for controlling the tempo there is provided a hook, 56, designed to engage an eye, 57, for connecting the link, 21, directly 90 to the motor governor whose controlling lever is rigidly associated with the movable tempo index, 58, on which the eye, 57, is secured. This detail is shown in Fig. 7, though the connection between the index, 100 58, and the governing devices of the motor, 2, are illustrated in detail in Figs. 11, 12, 13 and 14. But since the movement of the link, 21, necessarily involves movement of the bell crank, 20, and with it a shifting of the 105 friction wheel, 13, across the face, 12^a, of the gear, 12, it is desirable to separate the frictionally engaged surfaces of the wheel, 13, and gear, 12, and this is automatically effected by a cam roller, 59, carried by the cam lever, 46, in position to encounter one end of a tubular thrust link, 60, slidably mounted on the shaft, 8, and connected by a lever, 61, with a push rod, 62, arranged to act against the center of the face of the gear, 12, to push 110 said gear axially out of engagement with the friction wheel, 13, by slightly compressing its follower spring, 63. Since the push rod, 62, only comes into play when the shaft is disconnected from the motor, 2, the gear, 12, 115 stands idle and is in no way embarrassed by the action of the push rod, 62, and the friction wheel, 13, is left free for sliding movement following the movement of the link 21.
- When it is desired to operate the phonograph alone and independently of the piano, the handle, 55, is moved through the entire range bringing the pin, 47, into engagement with the notch, 46^b, of the cam lever, 46. This permits the gear, 9, to move back into 120 125 130

mesh with the gear, 2^a, for operatively connecting the motor, 2, with the phonograph table, 4. Simultaneously the cam member, 51, is shifted to bring its surface, 51^b, into contact with the follower roller, 52, on the shifter rod, 49, and since this surface, 51^b, is in a plane intermediate the planes of the surfaces, 51^a and 51^c, respectively, it puts the shifter, 49, into a position in which both the 10 clutches, 18 and 50, are disengaged from the take-up roll, 3, so that the motor, 2, causes no movement of the take-up roll, 3. From this position of the cam lever, 46, the cam roller, 59, is carried below the shaft, 8, and 15 beyond the end of the tube, 60, thereon allowing the latter to stand in its normal position with the thrust rod, 62, exerting no pressure on the face of the gear, 12.

When the motor, 2, is a spring motor it is 20 normally kept wound by automatic winding devices, not shown, and connected with the pumping mechanism of the player piano, but when the phonograph is used for any considerable length of time without the 25 player mechanism of the piano the spring motor will of course run down and must be rewound. Since the winding shaft, 64, extends to the end of the piano casing at 65, for convenient connection of the winding 30 clutches, 66, with the pumping mechanism in the lower part of the piano case, it is a simple matter to provide reduction gears, 67, 68 and 69, connecting the winding shaft, 64, with a short shaft, 70, and a removable 35 winding crank, 71, just outside the end panel, 65, of the piano case.

As indicated in Fig. 3, the sound box, 30, of the phonograph connects through its tone arm, 72, with an amplifier, 73, opening directly into the back of the frame which carries the take-up roll and note sheet spool. The sound-discharging opening, 74, is arranged to be varied as to its size for controlling the volume of sound discharged therefrom by provision of a curtain, 75, shown mounted on a roller, 76, and carrying in its free end a weighted rod, 77, whose ends are guided in guideways, 78, while the roller, 76, is arranged to be rotated through a train of 45 gears indicated on Fig. 3 at 79, and manually operable through a knurled knob, 80, conveniently located near the front of the frame and in the opening into which the note sheet spool is to be mounted.

50 I claim:—

1. In combination with a piano player action and note-sheet-carrying and propelling means, comprising take-up and re-wind rolls, a motor for actuating the re-wind roll; 55 a phonograph record carrier mounted in juxtaposition to the note-sheet-carrying means; a shaft operatively connected with the motor and with the record carrier for actuating the carrier by the motor; driving connections by which said shaft drives the

take-up roll and speed-varying devices in said connections.

2. In combination with a piano player action and note-sheet-carrying and propelling means comprising take-up and re-wind rolls, 70 a motor for actuating the re-wind roll; a phonograph record carrier mounted in juxtaposition to the note-sheet-carrying means; a shaft operatively connected with the motor and with the record carrier for actuating 75 the carrier by the motor; driving connections by which said shaft drives the take-up roll; speed-varying devices in said connections, and manually operable means for operating said devices.

3. In combination with a piano player action and note-sheet and note-sheet-carrying and propelling means comprising take-up and re-wind rolls, a motor for actuating the re-wind roll; a phonograph record carrier 80 mounted in juxtaposition to the note-sheet-carrying means; a shaft operatively connected with the motor and with the record carrier for actuating the carrier by the motor; driving connections from said shaft to 85 the take-up roll; speed-varying devices in said connections, and note-sheet-controlled means for operating said devices.

4. In combination with a piano player action and note-sheet-carrying and propelling 90 means comprising take-up and re-wind rolls; a motor for actuating the re-wind roll; a phonograph record carrier mounted in juxtaposition to the note-sheet-carrying means; a shaft operatively connected with the 95 motor and with the record carrier for actuating the carrier by the motor; driving connections from said shaft to the take-up roll, and speed-varying devices in said connections; a disengageable clutch in said 100 connections; another clutch for directly connecting the take-up roll with the motor, and means for shifting said clutches simultaneously to connect the take-up roll with one or the other of said driving means.

5. In combination with a piano player action and note-sheet-carrying and propelling means comprising take-up and re-wind rolls; a motor for actuating the re-wind roll; a phonograph record carrier mounted 105 in juxtaposition to the note-sheet-carrying means; a shaft operatively connected with the motor and with the record carrier for actuating the carrier by the motor independently of the take-up roll or its shaft; said 110 connections for the record carrier comprising speed-varying devices, and manually-operable means for adjusting said devices.

6. In combination with a piano player action and note-sheet-carrying and propelling means comprising take-up and re-wind rolls; a motor for actuating the re-wind roll; a phonograph record carrier mounted 115 in juxtaposition to the note-sheet-carrying means; a shaft operatively connected with 120

the motor and with the record carrier for actuating the carrier by the motor independently of the take up roll or its shaft; said connections with the record carrier comprising a friction disk on said shaft, a spindle for the carrier parallel with the face of said disk, a friction pulley on the spindle engaging with face of the disk and slidably on the spindle, and manually-operable means for sliding the pulley along the spindle.

7. In combination with a piano player action, note-sheet and note-sheet-carrying and propelling means comprising a take-up roll; a phonograph record carrier and means by which it is rotated in determined time-relation with the take-up roll; a reproducer comprising a stylus-holder mounted for co-operation with the record; means for lifting the stylus-holder to carry the stylus away from the record, and note-sheet-controlled means for so lifting it.

8. In combination with a piano player action, note-sheet and note-sheet-carrying and propelling means comprising a take-up roll; a phonograph record carrier and means by which it is rotated in determined time-relation with the take-up roll; a reproducer comprising a stylus holder mounted for co-operation with the record; means for lowering and lifting the holder to carry the stylus to and from the record, and note-sheet-controlled means for controlling the lowering and lifting of the holder.

9. In combination with a piano player action, note sheet and note-sheet-carrying and propelling means comprising a take-up roll; a phonograph record carrier and means by which it is rotated in determined time-relation with the take-up roll; a reproducer comprising a stylus-holder mounted for co-operation with the record; an arm extending over the record carrier for lodgment of the stylus carrier thereon; means for raising and lowering said arm to lift the stylus carrier from the record and lower it into contact therewith, and note-sheet-controlled means for so operating said arm.

10. In combination with a piano player action, a note sheet and note-sheet-carrying and propelling means comprising a take-up roll; a phonograph record carrier, a train of gearing by which both the phonograph record-carrier and the take-up roll are rotated in determined time relation with each other; a reproducer comprising a stylus-holder; a tone arm on which the reproducer is carried for co-operation with the record; said tone arm being pivoted for swinging freely over the record, and adapted to be fed thereover solely by the engagement of the stylus with the record; a bar extending over the record carrier for lodgment of the stylus carrier thereon; means for raising and lowering said bar to lift the stylus carrier from the record and lower it into contact therewith;

means for latching the bar in its elevated position for holding the stylus out of co-operation with the record; and manually-operable means for releasing the latch.

11. In combination with a piano player action, a note-sheet and note-sheet-carrying and propelling means comprising a take-up roll, a phonograph record carrier, and means by which it is rotated in determined time-relation with the take-up roll; a reproducer comprising a stylus-holder mounted for co-operation with the record; a bar extending over the record carrier positioned for affording lodgment of the stylus-holder thereon; a pneumatic operatively connected with said bar for controlling the lifting and lowering thereof, and note-sheet-controlled means for energizing said pneumatic.

12. In combination with a piano player action, a note-sheet and note-sheet-carrying and propelling means comprising a take-up roll; a phonograph record carrier and means by which it is rotated in determined time-relation with the take-up roll; a reproducer comprising a stylus-holder mounted for co-operation with the record; a bar extending over the record carrier positioned for affording lodgment of the stylus-holder thereon; a latch for holding the bar at elevated position; a pneumatic operatively connected with the latch for disengaging it; and note-sheet-controlled means for energizing said pneumatic.

13. In combination with a piano player action, a note-sheet and note-sheet-carrying and propelling means comprising a take-up roll; a phonograph record carrier and means by which it is rotated in determined time relation with the take-up roll; a reproducer comprising a stylus-holder mounted for co-operation with the record; a bar extending over the record carrier positioned for affording lodgment of the stylus-holder to hold the stylus out of contact with the record or lower it thereto; a latch for holding the bar at elevated position; a spring for yieldingly holding said latch engaged with the bar; a pneumatic operatively connected with the latch for disengaging it in opposition to said spring; and note-sheet-controlled means for energizing said pneumatic.

14. In combination with a piano player action, note-sheet and note-sheet-carrying and propelling means comprising a take-up roll; a phonograph record carrier; a train of gearing by which both the phonograph record-carrier and the take-up roll are rotated in determined time relation with each other; a reproducer comprising a stylus-holder; a tone arm on which the reproducer is carried for co-operation with the record; said tone arm being pivoted for swinging freely over the record and adapted to be fed thereover solely by the engagement of the stylus with the record; a bar extending over the record

- carrier positioned for affording lodgment for the stylus-holder, said bar being manually operable for lifting it to take the stylus-holder out of contact with the record, a spring-operated latch for engaging the bar to hold it in said lifted position, and manually-operable means for releasing the latch. 5
15. In combination with a piano player action, and note-sheet-carrying and propelling means comprising take-up and re-wind rolls; a motor for actuating the re-wind roll; a phonograph record carrier mounted in juxtaposition to the note-sheet-carrying means; a shaft operatively connected with the motor and with the record carrier for actuating the carrier by the motor independently of the take-up and rewind rolls or their shafts, the second mentioned connection comprising speed-varying devices, and means for adjusting said devices. 10 70 75
15. In combination with a piano player action and note-sheet-carrying and propelling means comprising take-up and re-wind rolls, a speed-governed note-sheet motor; a phonograph record carrier; a shaft operatively connected with the motor and with the carrier for actuation of the carrier by the motor independently of the take-up and rewind rolls or their shafts; driving connections from said 15 80 85 90 95 100
- 20 motor-connected shaft to the take-up roll comprising a friction disk which derives rotation from said shaft; a counter shaft parallel to the face of said disk; a friction pulley mounted for sliding on the last mentioned shaft and carried peripherally along the face of the disk toward and from the axis thereof, a shifting device connected with said pulley for so sliding it along its shaft; manually operable means for operating said shifting device. 25
- 30 16. In combination with a piano player action, note-sheet and note-sheet-carrying and propelling means comprising take-up and re-wind rolls; a motor for actuating the re-wind roll; a phonograph record carrier mounted in juxtaposition to the note-sheet-carrying means; a shaft operatively connected with the motor and with the record carrier for actuating the carrier by the motor; driving connections from said shaft to the take-up roll comprising a disk which is rotated in connection with said shaft, a second shaft extending parallel to the face of said disk, a friction pulley mounted for sliding on said second shaft with its periphery in contact with said disk, a shifter connected to said pulley for so sliding it, and note-sheet-controlled means for operating said shifter. 35 40 45 105 110 115 120
- 40 17. In combination with a piano player action and note-sheet-carrying and propelling means comprising take-up and re-wind rolls, a motor gear train for actuating the re-wind roll, a phonograph record carrier mounted in juxtaposition to the note-sheet-carrying means; a shaft which is not concerned in the actuation of said rolls operatively connected disengageably with the motor and independently of the roll-operating shaft of said train, and also operatively connected with the phonograph record carrier for actuating said carrier by the motor, and means for engaging and disengaging said shaft and the motor at will. 45 50 55 60 65 70 75 80 85 90 95 100 105 110 115 120 125
- 65 18. In combination with a piano player action and note-sheet-carrying and propelling means comprising take-up and re-wind rolls, a note-sheet motor, a phonographic record carrier; a shaft operatively connected with the motor and with the carrier for actuating the carrier by the motor; means 130

- for actuating the take-up roll directly from the note-sheet motor; means for actuating said roll from said first mentioned shaft, each of said means comprising a shiftable clutch, a bar by which both of said clutches are carried for simultaneous movement to engage one and disengage the other, a spring acting upon said bar to hold the direct driving clutch disengaged; a bearing support 5 on the motor frame and two cam devices 40 carried by said lever, one operating upon said clutch-carrying bar, and the other upon the shaft bearing for actuating said bar and bearing against the yielding resistance of said spring and said shaft, the 45 cam for operating said shaft bearing having two low points at each of which said shaft is engaged with the motor, the other cam having its lowest point corresponding with one of the low points of the first mentioned 50 cam, and a second point of intermediate elevation corresponding to the other of said low points, and adapted for holding said clutches at intermediate position at which both are disengaged when said shaft is engaged with the motor.
- 10 22. In combination with a piano player action and note-sheet-carrying and propelling means comprising take-up and re-wind rolls, a note sheet motor, a phonographic record carrier; a shaft operatively connected with the motor and with the carrier for actuating the carrier by the motor; means for actuating the take-up roll directly from the note-sheet motor; means for actuating said roll from said first mentioned shaft, the 60 15 shaft bearing for actuating said bar and bearing against the yielding resistance of said spring and said shaft.
- 20 22. In combination with a piano player action and note-sheet-carrying and propelling means comprising take-up and re-wind rolls, a note sheet motor, a phonographic record carrier; a shaft operatively connected with the motor and with the carrier for actuating the carrier by the motor; means for actuating the take-up roll directly from the note-sheet motor; means for actuating said roll from said first mentioned shaft, the 65 25 shaft bearing for actuating said bar and bearing against the yielding resistance of said spring and said shaft.
- 30 22. In combination with a piano player action and note-sheet-carrying and propelling means comprising take-up and re-wind rolls, a note sheet motor, a phonographic record carrier; a shaft operatively connected with the motor and with the carrier for actuating the carrier by the motor; means for actuating the take-up roll directly from the note-sheet motor; means for actuating said roll from said first mentioned shaft, the 70 35 shaft bearing for actuating said bar and bearing against the yielding resistance of said spring and said shaft.
- 35 22. In combination with a piano player action and note-sheet-carrying and propelling means comprising take-up and re-wind rolls, a note sheet motor, a phonographic record carrier; a shaft operatively connected with the motor and with the carrier for actuating the carrier by the motor; means for actuating the take-up roll directly from the note-sheet motor; means for actuating said roll from said first mentioned shaft, the 75 shaft bearing for actuating said bar and bearing against the yielding resistance of said spring and said shaft.

23. In combination with a piano case, a player action and a spring motor for the note-sheet propelling devices thereof mounted within the case; a phonograph record carrier and connections from said motor for actuating said carrier, the motor having disengageable driving connections to the note-sheet-propelling devices, whereby the motor may actuate the phonograph record carrier 60 without actuating said note-sheet-propelling devices; a winder for the motor mounted within the piano case at one end thereof; and a shaft from said winder to the motor for winding the latter, said winder having a 65 shaft which is accessible from the outside of the piano case for operating it to wind the motor.

In testimony whereof I have hereunto set my hand at Chicago, Illinois, this 3rd day 75 of February, 1916.

MELVILLE CLARK.
